UNITED STATES PATENT OFFICE.

VERNON ROYLE, OF PATERSON, NEW JERSEY.

COP.

1,214,958.

Specification of Letters Patent.

Patented Feb. 6, 1917.

Application filed August 22, 1914. Serial No. 858,107.

To all whom it may concern:

Be it known that I, VERNON ROYLE, a citizen of the United States, and resident of Paterson, in the county of Passaic and State 5 of New Jersey, have invented a new and useful Cop, of which the following is a specification.

My invention relates to a cop and more particularly to a cop for use in shuttles, with 10 the object in view of providing a core sleeve cop with a core or spindle suitable for insertion into a shuttle to permit the cop to freely unwind, the core being further provided with a clutch member for use in connection with winding thread thereon to 15 produce a cop.

In the accompanying drawings,

Figure 1 is a view of the cop and its core in side elevation partly in section.

20 Fig. 2 is an end view of the same, and Fig. 3 is a view of the core on which the cop is to be wound.

In the use of cops wound on paper tubular cores as has heretofore been common, 25 when the cop is placed on the spindle within the shuttle, trouble has arisen from the sliding of the cop along the spindle cramping the thread and the paper core has further been subject to atmospheric changes, 30 swelling in damp weather and contracting in dry weather. Furthermore, the core sleeve wound on the smooth surfaced spindle has not been found feasible because of the slipping of the thread thereon.

35 My present invention, therefore, is directed particularly to the structure of the core which shall intimately coact with the core sleeve wind to produce a cop and core combined, the core being of such a nature that 40 it may be rewound and used over and over again.

The body of the core sleeve wound cop is denoted by 1. The core is made up of a spindle 2 provided with journals 3 and 4 at 45 its opposite ends for seating in suitable bearings in a shuttle, the said spindle being provided with a jacket or covering of such a nature that the thread of the cop 1 will not have a tendency to slip longitudinally 50 along the core when it is wound thereon. The spindle 2 is conveniently made of steel and the covering is, in the present instance, a coarse thread 5 wound spirally thereon,

the successive spirals being in close juxtaposition but leaving slight indentations 6 between two successive spirals throughout the length of the core. The coarse thread 5 may be treated in any well known or suitable way to render it proof against moisture or a non-conductor of electricity, and while I have 60 shown the jacket or covering on the spindle as formed of threads, I do not wish to limit myself to a wound covering, as my invention contemplates a permanent covering on the spindle 2 which shall produce a 65 roughened or frictional surface sufficient to prevent the thread of the cop 1 from slipping out of position during the winding operation.

To fit the core ready for attachment to a 70 winding machine, I provide a clutch member on each end of the spindle 2, in the present instance, by flattening a reduced portion 7 of the end of the spindle, as shown at 8.

To hold the jacket or covering 5 in position on the spindle 2, end sleeves 9 and 10 are driven on to the reduced portions 7 at the ends of the spindle against the shoulder 11, and the outer ends of said sleeves 9 and 10 are cut away internally, as at 12, to 80 leave room for the clutch member, not shown, on the winding machine to slip over and co-act with the clutch member 8 on the spindle.

By the above construction the core 85 combines in itself a support for the cop during the winding of the cop and also during the unwinding of the cop without any shifting other than simply to place the cop and its core in position in the shuttle, and when the 90 body of thread on the cop is used, the jacketed core may be used for winding another cop.

What I claim is:

1. A cop core comprising a cop receiving 95 sleeve provided with a roughened surface to permit a coarse wind thereon and a spindle intimately united with the sleeve, the spindle being provided with journals at its ends for use in a shuttle and with a clutch member 100 for use in a winding machine, whereby the core may be used both as a cop receiving and cop delivering element without change.

2. A cop core comprising a cop receiving sleeve provided with a roughened surface to 105 permit a coarse wind thereon, and a spin-

dle, the spindle being provided with journals at its ends for use in a shuttle, with a clutch member for use in a winding machine and with end sleeves for holding the cop receiving sleeve securely in position on the spindle.

In testimony that I claim the foregoing

as my invention, I have signed my name in presence of two witnesses, this twenty-ninth day of July, 1914.

VERNON ROYLE.
